UNITED STATES PATENT OFFICE.

EDWIN F. HULBERT, OF DETROIT, MICHIGAN, ASSIGNOR OF ONE-HALF TO
L. C. BROOKS, OF DETROIT, MICHIGAN.

CRATE STRUCTURE.

No. 796,578.

Specification of Letters Patent.

Patented Aug. 8, 1905.

Application filed November 28, 1904. Serial No. 234,591.

To all whom it may concern:

Be it known that I, EDWIN F. HULBERT, a citizen of the United States, residing at Detroit, in the county of Wayne and State of Michigan, have invented certain new and useful Improvements in Crate Structures, of which the following is a specification.

This invention provides improvements in crates or box structures, and embodies a delivery-package of this type constructed with a view to securing a receptacle having a maximum degree of lightness and at the same time reinforced in such a manner as to promote its lasting or wear qualities to the greatest possible extent.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features thereof, still the preferred embodiment thereof is shown in the accompanying drawings, in which—

Figure 1 is a vertical sectional view of a receptacle embodying the invention, the lining of the receptacle being broken away centrally. Fig. 2 is a plan view of the invention. Fig. 3 is a broken perspective view showing the corner portion of a crate structure embodying the invention. Fig. 4 is a perspective view, partially broken away, showing a portion of the metallic lining of the crate located adjacent the corner of the receptacle. Fig. 5 is a broken horizontal sectional view of a corner portion of the crate. Fig. 6 is a broken perspective view showing more clearly the manner of attaching the lower ends of the truss-wires to cleats on the bottom of the crate.

Corresponding and like parts are referred to in the following description and indicated in all the views of the drawings by the same reference characters.

The improvements which comprise the invention relate more particularly to that class of crates or like structures in which the body of the receptacle is composed of walls made of slats suitably secured together and reinforced in such a manner as to afford a device

having substantially the same rigidity as many solid box structures, though less expensive, and having greater wearing qualities.

The crate shown in the drawings is of somewhat oblong formation; and it consists, essentially, of the side walls 1, the end walls 2, and the bottom wall 3. The end walls 2 and the bottom wall 3 are preferably made of a plurality of slats 4, secured together by suitable means. The slats which comprise the several walls of the crate structure are secured together by means of truss-wires 5, disposed at intervals in the length of the walls, which truss-wires 5 brace the walls vertically, as well as form connecting means for the slats. It is preferred to use two truss-wires 5 at the several points along the walls 2 and 1, and these wires have their upper ends looped about longitudinal and transverse rails 6 and 7, respectively, the latter located at the upper portions of the several walls aforesaid. Said truss-wires 5 are attached to the slats 4 by means of binding-wires 8, wrapped around the truss-wires at the several points between the adjacent slats 4. The slats 4 are thus firmly attached to the truss-wires 5 by means of the binding-wires 8, the strength of the wall structure being greatly increased in this way. The lower extremities of the truss-wires 5 are secured to longitudinal cleats 9, secured to the bottom wall 3 of the crate by fastenings. At the ends of the several walls 1 and 2 are located vertical posts 10, said posts being secured to the ends of the slats which compose the walls, adjacent which the respective member 10 is located. The posts 10 of course coöperate with the truss-wires 8 in bracing and reinforcing the walls of the receptacle, and the rails 6 and 7 are likewise suitably secured to the parts 10 at the upper ends of the latter. The end portions of the adjacent rails 6 and 7 are secured together by means of angle-plates 11, and in order to protect the corner portions of the walls 1 and 2 similar means may be provided. The protecting means used, however, forms a part of an inner metallic lining 12, the end portions of the sides of the lining being bent or folded about the end portions of the slats of the wall adjacent the lining, as shown at 13. The lining 12 is spaced from the walls 1 and 2 because of the provision of the corner members 10, said members

10 being located between the lining and the slats 4, which compose the walls. It will be understood that the lining also incloses the posts 10 when it has been folded about the end portions of the slats 4, as above described. The posts 10 extend some distance above the uppermost of the slats 4 in order that the rails 6 and 7 may be attached thereto, and the rails aforesaid are of several times the size of the slats in order that the upper end of the crate may be reinforced, this portion of the receptacle being subjected to greater wear and service than any other part perhaps. The upper portion of the sides of the lining 12, which is bent at the ends, folds about the posts 10 adjacent or at that portion of the post against which the rail 6 or 7, as the case may be, is secured, the remaining portion of the lining being of course folded about the ends of the slats. The portion of the lining 12 which is secured between the corner-post 10 and the rail 6 or 7 is indicated by the numeral 13^a. (See Fig. 4.) It is preferred to utilize also a lining 14, made of paper or some fibrous material, which is designed to exclude heat and protect the contents of the receptacle in a manner which will be obvious. The lining 14 is especially useful when the crate is used to receive goods which may become damaged by the elements or the like. The lining 14 is secured in the crate structure between the lining 12 and the walls of the receptacle. In securing the parts of the walls 1, 2, and 3 together vertical angle-plates 15 are disposed at the corners of the crate interior thereof, and these plates 15 abut against the extreme end portions of the sides of the lining 12 adjacent the portion bent therefrom, as shown at 13, to form a protection for the ends of the walls 1 and 2 at the corners. Fastenings extend through the plates 15, the linings 12 and 14, the posts 10, the portions 13 of the lining at the upper portion of the crate, also through the rails 6 and 7, and the angle-plates 11, securing said rails at the corners. The fastenings mentioned are indicated at 16 and are preferably rivets or similar devices permanently securing the parts together in the manner stated.

The side walls 1 of the crate preferably have the end portions thereof received between the end walls 2 at the corners, and it will be understood that the linings 12 and 14 are provided at the bottom wall 3 in a manner similar to the disposition of these parts along the sides. Angle extensions 17 project from the lower extremities of the interior angle-plates 15, and these extensions are riveted or suitably secured to the bottom wall of the receptacle, and this bottom wall 3, which forms a part of the ends 2 of the crate, is braced by the provision of the parts 17 and the manner of securing the same to the crate structure.

In certain instances it is desirable that the

crate be provided with runners 18, and the latter extend lengthwise of the bottom wall 3 thereof, being secured by suitable fastenings. The bolts or rivets which attach the extensions 17 to the bottom wall 3 may pass through the runners 18 in order to secure the latter to the crate, as shown most clearly in Fig. 1 of the drawings. Runner-irons 19 are attached to the under sides of the runners 18, and the ends of these irons extend upwardly, as shown at 19^a, being attached to the end walls 2 of the crate. The upper extremities of the parts 19^a of the runner-irons terminate just beneath the rails 7, and the latter are thus to a certain extent braced by said irons. To eliminate projecting parts, the irons 19 are made of rounded form upon the exposed sides. (See Fig. 3.)

The receptacle as above described embodies a construction in which the corners are absolutely rigid, though the walls are comparatively light, so as to have a certain degree of spring or elastic strength. The whole structure of the crate is reinforced peculiarly by the manner of securing the various parts, so as to coöperate with each other in increasing the general rigidity of the article.

Having thus described the invention, what is claimed as new is—

1. In crate structure, the combination of side, end and bottom walls composed of slats, vertical posts at the ends of the slats composing the said walls, said posts projecting some distance above the uppermost of the slats of the several walls aforesaid, rails secured to the upper projecting portions of the posts, corner-irons connecting adjacent ends of the rails, angle-plates secured to the inner side of the adjacent vertical posts aforesaid, and runner-irons extending longitudinally of the bottom of the crate and having the end portions thereof extended upwardly at the ends of the crate and terminating just beneath the end rails aforesaid.

2. In crate structure, the combination of side, end and bottom walls composed of a plurality of slats, longitudinal cleats secured to the under side of the slats of the bottom wall, vertical posts at the ends of the slats of the side and end walls and projecting above the uppermost of the slats, rails attached to said projecting portions of the posts aforesaid, angle-irons securing the adjacent extremities of the rails, truss-wires arranged at intervals in the length of the side and end walls, and binding-wires securing the truss-wires to the walls, the upper extremities of the truss-wires being attached to the adjacent rails and the lower extremities to the longitudinal cleats above described.

3. In crate structure, the combination of side, end and bottom walls composed of a plurality of slats, longitudinal cleats secured to the under side of the slats of the bottom

wall, vertical posts at the ends of the slats of the side and end walls and projecting above the uppermost of the slats, rails attached to said projecting portions of the posts aforesaid, angle-irons securing the adjacent extremities of the rails, truss-wires arranged at intervals in the length of the side and end walls, binding-wires securing the truss-wires to the walls, the upper extremities of the truss-wires being attached to the adjacent rails and the lower extremities to the longitudinal cleats above described, runners arranged beneath the bottom wall of the crate, and runner-irons secured to the under sides of said runners and having their end portions projecting upwardly and terminating just beneath the end rails.

4. In crate structure, the combination of side, end and bottom walls composed of slats or the like, a lining interior of said walls and having the end portions of the sides thereof folded about the ends of the walls, angle-plates secured to the adjacent end portions of the walls, and extensions at the lower end of said angle-plates secured to the bottom wall of the crate by fastenings passing through the bottom portion of the lining aforesaid.

5. In crate structure, the combination of side, end and bottom walls composed of a plurality of slats suitably secured together, an interior lining comprising the sides having the ends thereof bent outwardly and folded about the end portions of the slats composing the adjacent wall of the crate, vertical posts received between the folded portions of the sides of the lining at the ends of the walls aforesaid, and fastenings passing through the lining, vertical posts, and end portions of the slats.

6. In crate structure, the combination of side, end and bottom walls, vertical posts secured to the ends of the side and end walls, a

lining comprising the sides having the end portions thereof folded outwardly so as to inclose or receive the vertical posts and adjacent end portions of the walls of the receptacle, angle-plates interior of the receptacle and located against the end portions of the sides of the lining, and fastenings passing through the angle-plates, the vertical posts, and lining to secure said parts together.

7. In crate structure, the combination of end and side walls, vertical posts secured to the end portions of the walls at the corners of the receptacle and projecting above the upper portions of said walls, rails secured to the upper projecting portions of the posts, a lining comprising sides having the end portions thereof folded outwardly so as to embrace the adjacent end portions of the walls, angle-irons securing the adjacent ends of the rails aforesaid, angle-plates interior of the receptacle at the corner portions thereof, and fastenings common to the angle-plates, the lining, the rails, the angle-irons securing said rails together, and the walls of the receptacle.

8. In crate structure, the combination of side, end and bottom walls, vertical posts at the ends of the side and end walls and projected above the upper extremities thereof, rails attached to the projecting portions of the posts aforesaid, runners arranged longitudinally beneath the bottom wall of the crate, and runner-irons secured to the under sides of said runners and having the end portions projecting upwardly and terminating just beneath the end rails of the crate to brace the latter.

In testimony whereof I affix my signature in presence of two witnesses.
